CLAIM

The ornamental design for a hairdryer nozzle, as shown and described.

DESCRIPTION

1. Hairdryer nozzle
- 1.1 : Front
- 1.2 : Back
- 1.3 : Right
- 1.4 : Top
- 1.5 : Bottom
- 1.6 : Perspective

Our new design is related to a hairdryer nozzle used as an accessory of a hairdryer for drying and/or styling hair; The design characteristic lies in the shape and the reproduction best showing the design characteristic is the perspective view; The left view is omitted due to the symmetry with the right view.
